United States Patent Office

Des. 177,041
Patented Mar. 6, 1956

177,041

CAN OPENER

John M. Grace, Chicago, Ill., assignor to Vaughan Mfg.
Co., Chicago, Ill., a corporation of Illinois

Application July 20, 1955, Serial No. 37,051

Term of patent 14 years

(Cl. D22—2)

FIG. 1.

FIG. 2.

FIG. 3.

FIG. 4.

FIG. 5.

Fig. 1 is a top plan view of a can opener showing my new design;

Fig. 2 is a side elevational view thereof;

Fig. 3 is a bottom plan view;

Fig. 4 is a side elevational view showing the side opposite to that of Fig. 2; and

Fig. 5 is an end elevational view thereof as it appears when viewed from the left side of Fig. 4.

I claim:

The ornamental design for a can opener, substantially as shown.
